UNITED STATES PATENT OFFICE

EDGAR H. GORSUCH AND FRED F. SLACK, OF GRAND RAPIDS, MICHIGAN, ASSIGNEES TO
CORDUROY TIRE COMPANY, OF GRAND RAPIDS, MICHIGAN, A CORPORATION OF
DELAWARE

DESIGN FOR A TIRE

Application filed February 5, 1931. Serial No. 38,564. Term of patent 3½ years.

To all whom it may concern:

Be it known that we, EDGAR H. GORSUCH and FRED F. SLACK, both being citizens of the United States, and residing at Grand Rapids, in the county of Kent and State of Michigan, have invented a new, original, and ornamental Design for a Tire, of which the following is a specification, reference being had to the accompanying drawings, forming part thereof.

In said drawings, Figure 1 is a fragmentary plan view of a tire, showing our new design;

Figure 2 is a fragmentary side elevational view of the tire; and

Figure 3 is a cross sectional view thereof.

We claim:

The ornamental design for a tire, as shown. Executed at Grand Rapids in the county of Kent and State of Michigan, this 3rd day of February, 1931.

EDGAR H. GORSUCH.
FRED F. SLACK.
